UNITED STATES PATENT OFFICE.

OMAR A. BURGESS, OF PUYALLUP, WASHINGTON.

AMALGAMATOR.

1,412,673.

Specification of Letters Patent. Patented Apr. 11, 1922.

Application filed June 23, 1921. Serial No. 479,852.

To all whom it may concern:

Be it known that I, OMAR A. BURGESS, a citizen of the United States, residing at Puyallup, in the county of Pierce and State 5 of Washington, have invented certain new and useful Improvements in Amalgamators; and I do hereby declare the following to be a full, clear, and exact description of the invention, such as will enable others skilled in 10 the art to which it appertains to make and use the same.

This invention relates to a machine for extracting precious metal from ore and other medium containing the same.

15 The invention appertains most especially to amalgamators of the rotary type and provides a separator embodying a casing, separating drums rotatably mounted therein, a pump for circulating mercury and an electrolytic in conjunction with the mercury circuit to eliminate the metal and cause the mercury to flow freely.

Other objects and advantages will be apparent and suggest themselves as the nature 20 of the invention is understood.

While the drawings illustrate an embodiment of the invention it is to be understood that in adapting the same to meet different conditions and requirements, various changes 25 in the form, proportion and minor details of construction may be resorted to without departing from the nature of the invention.

Referring to the accompanying drawings forming a part of the specification,

30 Figure 1 is a vertical central transverse section of an amalgamator embodying the invention.

Figure 2 is an elevation as seen from the discharge side.

35 Figure 3 is a view similar to Figure 2 as viewed from the opposite or feed side.

Figure 4 is a view similar to Figure 3 the near end plate being omitted and parts being broken away, and

40 Figure 5 is a detail view of a portion of one of the separating drums.

Corresponding and like parts are referred to in the following description and designated in the several views of the drawings 45 by like reference characters.

The machine comprises a casing which embodies a cylinder 1, base 2 and end plates 3 and 4. The cylinder 1 and base 2 preferably consist of a single casting which is adapted to be secured to a suitable bed or foundation. The ends of the cylinder 1 are machined or

otherwise made true to insure the formation of a tight joint between them and the heads 3 and 4. The heads 3 and 4 are heavy and may consist of castings or may be stamped from plate metal. The heads are bolted or otherwise firmly secured to the cylinder 1 and their central portions are made heavy to provide substantial bearings for a shaft 5 which is mounted therein and extends beyond 60 opposite sides of the casing. A belt pulley 6 is fast to one end of the shaft 5 and an eccentric 7 is fixedly mounted upon the opposite end portion thereof. The inner faces or walls of the cylinder or casing are lined with 70 copper which is applied in a manner to admit of ready replacement when required.

A feed pipe 8 leading from a suitable source of supply extends through the central portion of the head 4 and projects into the 75 casing some distance to properly deliver the ore or other metal bearing medium to the separator. The horizontal portion 8a of the feed pipe 8 is disposed to one side of the shaft 5 and terminates within the casing at 80 a point about midway the ends or heads thereof. A discharge pipe 9 connects with the upper portion of the head 3 and is considerably larger than the feed pipe 8 so as to offer a minimum resistance to the outflow to 85 the tailings such as crushed rock, sand and other material containing the precious metal together with water whereby the same is flooded.

The separating means are disposed within 90 the casing and are mounted upon the shaft 5 and rotate therewith and comprise disks 10 and 11 and a plurality of concentric drums 12. The disks 10 and 11 are connected by means of bolts or tie rods 13 and 95 the drums 12 are clamped or otherwise secured theretwix. The disks 10 and 11 may consist of any metal and their inner faces are lined with copper. The disk 10 is clamped to the shaft 5 between a pair of 100 nuts 14 and the drums 12 are secured thereto in any manner and are preferably flanged and apertured to receive bolts or like fastening means whereby replacement when necessary may be easily effected. The disk 11 has its central portion cut away to provide ample clearance for the horizontal portion 8a of the feed pipe. A cup washer 15 is interposed between the end plate 3 and the disk 10. A similar cup washer 16 is disposed between the disk 11 and the end plate 105 or head 4. These cup washers centralize 110

the separator and maintain close joint between the same and the heads or end plates of the casing. The drums 12 preferably consist of cylinders of sheet copper of suitable 5 gage and construction. These cylinders are perforated to provide a passage for the crushed rock, sand or other metal bearing medium. The separating drums 12 are preferably silver plated and coated with mercury 10 whereby to provide for the separating of the precious metal of the ore, sand or the like in the form of an amalgam as well understood in the art of collecting precious metals from their ore by the process of amalgamation. The separating drums 12 are disposed 15 so that the openings therein break joint thereby obviating the provision of a direct passage for the escape of the material.

A mercury pipe 17 connects with the feed 20 pipe 8 and supplies mercury to the material as it enters the separator. A pump 18 is provided in the length of the pipe 17 and is actuated by means of the eccentric 7. The mercury pipe 17 connects with the lower 25 portion of the casing whereby to draw the mercury therefrom which is repeatedly used in the operation of the machine.

An electrifier 19 is associated with the 30 mercury pipe 17 and assists materially in the elimination of the amalgam from the mercury whereby the latter is rendered fluid so as to be supplied to the feed pipe 8 in substantially a pure condition so as to obtain the best results in the separation of the precious metal from the ore, sand or other medium bearing the same.

In the operation of the machine the separating drums 12 and the inner faces of the disks 10 and 11 are amalgamated and eliminate 35 the precious metal from the ore fed to the machine through the pipe 8, the separator rotating by power imparted to the shaft 5 through the instrumentality of the pulley 6. It is observed that the material is supplied 40 to the innermost part of the separator and passes outwardly through the series of drums in consecutive order and is discharged

from the upper portion of the casing by means of the pipe 9. As the precious metal is eliminated from the ore the amalgam produced gravitates to the bottom of the casing and is drawn therefrom through the pipe 17 and collects in the electrifier 19 from which it may be removed at stated intervals so long as the machine is in operation. The mercury supplied to the machine together with the material replenishes that used in the formation of an amalgam in the elimination of the precious metal from the ore. The construction of the machine is such as to 55 permit of repairs and replacements being readily effected as occasion requires.

Having thus described the invention, what I claim is:—

1. An ore separator comprising a casing 65 having a discharge in its outer portion, a rotary separator, within the casing and comprising a plurality of perforated drums having an approximate concentric arrangement with their faces amalgamated, means for supplying the material to the central portions of the casing and separator, and means for supplying mercury to the material preliminary to its delivery and feed to the machine.

2. An ore separator of the character specified comprising a casing having a discharge at its outer portion and a centrally disposed feed, a shaft journaled in the ends of the casing, a disk secured to an end portion of 70 the shaft, a plurality of separating drums attached to the disk and rotatable therewith and a second disk having its central portion cut away so as not to obstruct the feed and connected to the first mentioned disk whereby 75 to clamp the separating drums between the two disks.

In testimony whereof I affix my signature in presence of two witnesses.

OMAR A. BURGESS.
